James R. Clegg, Atty.

UNITED STATES PATENT OFFICE.

PHILIP K. WRIGLEY, OF CHICAGO, ILLINOIS.

DESIGN FOR A CARTON.

53,724.

Specification for Design.

Patented Aug. 19, 1919.

Application filed May 28, 1919. Serial No. 300,494. Term of patent 14 years.

To all whom it may concern:

Be it known that I, PHILIP K. WRIGLEY, a citizen of the United States, and a resident of Chicago, in the county of Cook and State of Illinois, have invented a new, original, and ornamental Design for a Carton, of which the following is a specification, reference being had to the accompanying drawing, forming part thereof.

The figure is a perspective view of my carton showing my new design.

I claim:

The ornamental design for a carton, as shown.

PHILIP K. WRIGLEY.
